PARACHUTE CARRIER AND RELEASE

Filed Aug. 8, 1927

UNITED STATES PATENT OFFICE.

FRANK B. FISHER, JR., OF KANSAS CITY, KANSAS.

PARACHUTE CARRIER AND RELEASE.

Application filed August 8, 1927. Serial No. 211,403.

This invention relates to aerial amusement devices, and more especially to a device for use in conjunction with flying kites. It is well known that a "messenger" strung on a kite string and released will, under the force of the wind, climb the string, and the sending of paper messengers seems to be of never failing interest and entertainment to children.

With this method of sending "messengers" and the interest exercised by adults as well as children in parachutes in mind, it was conceived that if parachutes could be sent up to kites and upon arrival be released, the interest of children in kite flying would be greatly increased and an amusement would be provided which would be of considerable importance in keeping the children off of the streets where so many fatalities and injuries occur.

Accordingly I have provided a traveler for ascending and descending a kite string, equipped with a parachute and adapted to be carried by the latter up to the kite, together with means for automatically releasing the parachute to permit the latter to float away and the traveler to gravitate back to the ground along the kite string.

With the general object named in view, the invention consists in certain novel and useful features of combination and organization of parts, as hereinafter described and claimed; and in order that it may be fully understood, reference is to be had to the accompanying drawing, in which:

Figure 1 is a perspective view of a flying kite, a parachute and a carrier for ascending the kite string under the pull of the parachute and sliding down the string when the parachute is released.

Figure 2 is a plan view of the carrier.

Figure 3 is a side view of the carrier.

Figure 4 is an enlarged fragmentary side view of the carrier and parachute as arranged in Figure 1.

Figure 5 is a cross section on the line V—V of Figure 2.

In the said drawing, where like reference characters identify corresponding parts in all of the figures, 1 indicates the body of the traveler and which may be made of wood, papier-mâché, or of any other suitable substance possessing sufficient lightness. Secured to the body 1 adjacent its opposite ends 55 and in alined relation are a pair of loops 2 preferably being left slightly open as at 3

for engagement with a kite string as will hereinafter appear. Between one of the loops 2 and the end of the body, a wire member 4 is passed through the body 1 and has its end 60 anchored by engagement with the adjacent loop 2, the other end of said wire member being coiled at an intermediate point as at 5, to form a hinge. The lower end terminates in an angular jaw 6 of a clamp member. Another wire is bent to form a similar opposing jaw 7 of said clamp member, being also formed with a pivot portion 8 received within the coiled hinge portion 5 of the member 4. The upper end of the wire providing the sec- 70 ond jaw forms an inverted loop-shaped arm 9 overlying the body 1 in alinement with loops 2, and constituting a trip, preferably of somewhat greater diameter than the loop 2. The jaws of the wire members 4 and 7 are bent 75 angularly at 10 and 11 respectively in opposite directions, and at their free extremities are slightly flared to securely hold a rubber or other resilient band 12 or the like, for resiliently maintaining the jaws in clamped relation. It is to be understood from a consideration of the drawing that a slight pressure on the loop 9 applied toward the loops 2, opens the jaws of the clamp member against the action of the rubber or other resilient member 80 10. In this connection it is to be understood that I illustrate and describe the mechanism just referred to as a matter of convenience to show one operative form of clamp for use with the device.

The parachute is indicated at 13, said parachute being equipped with a plurality of "falls" 14 and may be made of any suitable fabric or of tissue paper or the like. Secured to the ends of the falls is a weight 15 95 to insure proper descent of the chute, and in practice it is found desirable to make the weight 15 conform in general outline to the form of or to simulate a man as in the descent of the device such simulation appears natural 100 and lifelike and adds greatly to the interest manifested by children in the operation of the structure.

In order to attach the chute to the traveler so that the force of the wind shall raise the 105 chute and traveler to the point of release, the kite string 15 is engaged with the loops 2 by passage through the spaces 3 provided for this purpose, said string also being engaged with the loop or trip 9. The distance 110 between the trip 9 and the adjacent loop 2 is regulated so that under normal conditions

the arc of the kite string will not be sufficiently abrupt to cause the trip to ride on the kite string, and possibly release the chute as will hereinafter appear, but is sufficiently taut 5 to substantially insure the centering of the kite string within the trip 9.

Secured in any suitable manner to the kite string and preferably substantially below the kite to prevent possible entanglement of the 10 chute with the kite or its tail, is a trip pin or cross piece 16. After engaging the traveler with the kite string as set out, the operator engages a corner or edge of the chute with the clamp jaws 6 and 7 and unfolds and straightens out the chute, the distance from the clamp 15 to a projecting pin 18 secured adjacent the bottom of the traveler, being such that when the chute is engaged with the clamp one of the falls of the latter will just span the distance 20 so that it is fairly taut, a loop 19 being formed adjacent the ends of the falls to be slipped over said pin 18 to maintain the lower ends of the falls and the weight connected to the lower end of the traveler.

25 After the chute has been attached to the traveler as described, it is bellied out by hand until it is caught by the force of the wind. The force of the wind against the chute effects the upward travel of the traveler along 30 the kite string engaged by the supporting loops 2, the taut fall taking most of the load so that the corner of the chute will not be disengaged from the clamp.

35 It will be evident that the speed of ascent of the traveler and chute will be altogether dependent on the force of the wind, and said device will continue to ascend until the trip 9 contacts with the trip pin or cross piece 16, which effects opening of the clamp jaws and the 40 consequent release of the chute. As soon as the chute is released, the taut fall momentarily slackens and the weight 13 assisted by the forward inclination of the pin 18, will effect disengagement of the loop 19 from the lower 45 end of the traveler, the chute thereupon continuing its natural descent and the traveler returning along the kite string to the ground for a repetition of the ascent, if desired.

From the above description it will be ap-

parent that I have produced a device of the 50 character outlined, which possesses all of the features of advantage pointed out as desirable; and while I have described and claimed the preferred embodiment of the same, I reserve 55 the right to make all changes properly falling within the spirit and scope of the appended claims.

I claim:

1. In a device of the character described, a 60 carrier, means for slidably engaging said carrier with a support, a clamp adjacent one end of said carrier for detachable engagement with a parachute, and means adjacent the other end of said carrier for detachable engagement with the falls of such parachute. 65

2. In a device of the character described, the combination of a flying kite, a carrier 70 slidably suspended from the kite string, yieldingly-closed clamp jaws on the carrier, a projecting pin on the carrier spaced from 75 said jaws, a parachute held in suspension by the clamp jaws, and provided with falls looped on the said pin with the fall nearest the carrier in taut condition, a trip for the clamp jaws, and means on the kite string to 80 intercept the upward travel of the carrier imparted thereto by the parachute under pressure of the wind to effect operation of the trip.

3. In a device of the character described, a 80 carrier, means for slidably engaging the carrier with a support, a parachute having an extension member, means adjacent one end of the carrier for releasably engaging the 85 parachute, and means at the other end of said carrier for releasably engaging the extension member of said parachute.

4. In a device of the character described, the combination of a flying kite, a carrier 90 slidably suspended from the kite string, a 95 parachute having an extension member, means on the carrier releasably engaging said parachute, and a pin on the carrier spaced from the chute holding means and engaging the extension means of the chute.

In testimony whereof I affix my signature.

FRANK B. FISHER, JR.
